THERMOMETER

Application filed February 26, 1930. Serial No. 431,443.

This invention relates to thermometers and more in particular to a method of making thermometer tubing. In its preferred application the invention has to do with tubing 5 of elliptical or semi-elliptical cross-section.

According to the Patents 222,420 and Re. 10,189, a very large magnification of the bore and the mercury column may be obtained by having the bore disposed farther 10 back of the lens front than the mechanical center of the tube. In fact, it has been found that a maximum magnification can be obtained by making the tube of elliptical cross-section and placing the bore into one of the 15 foci thereof. When viewing the thermometer thus constructed through the curvature most remote from the bore, the visual width of the column of mercury or other liquid extends across the whole width of the tube so 20 that the liquid appears to transversely fill the whole tube.

Heretofore apparently no attempt has been made to produce a tubing of small bore wherein the bore is disposed at one of the foci 25 of an ellipse and the reason for that is probably the following:

In the first instance, the method used in making the regular thermometer tubing in which the bore is approximately located in 30 the center, cannot be used because there is no way of locating the bore with certainty at one of the foci of an ellipse. The only available method of forming a tube of a definite cross-section and placing the bore at a 35 definite point therein, is to place a mass of glass into a mould of the required cross-sectional configuration, then forcing a metal rod into the mass of glass in the mould, then applying the blowpipe, or, in fact, any other 40 piece of metal rod or tube by which the ball of glass may be pulled out of the mould and suspended for the drawing operation, and then taking the glass out of the mould together with the blow pipe and drawing the 45 tubing in the usual way.

This method, however, has heretofore not been a success because great care must be exercised lest the metal rod adheres to the hot glass. The rod must be moved through 50 the body of the glass long enough to slightly

chill the surface of the bore formed by the rod and to wipe the surface to well define the bore so as to make it the equivalent of a blown bore.

While the relatively large rod may at times 55 be successfully employed for this purpose, this method is not available for producing thermometers of smaller bores. A rod for forming the initial bore in the mass of hot glass to be drawn, must be of such small diameter that even the shortest stab into and out of the hot glass would cause a heating up 60 of the rod to such an extent as to cause it to stick in the glass.

The general object of the present invention is a method of producing small-bore thermometer tubing wherein the bore is disposed in a definite relation to the cross-sectional area of the tubing.

A more specific object is a method of producing thermometer tubing having an elliptical or semi-elliptical cross-section, wherein the bore is disposed in one of the foci of the ellipse.

The principal object of the invention is a 75 clinical thermometer or a thermometer having a small bore of the order of clinical thermometer bores, wherein the cross-section of the tubing is elliptical or semi-elliptical and the bore is disposed in one of the foci of the 80 ellipse.

The invention, the underlying principle of operation, the effect and the advantages derived from it and its technical and commercial importance may be more fully understood 85 from the accompanying drawings wherein

Fig. 1 is an elevation of a thermometer embodying the invention;

Fig. 2 is a cross-section thereof on a larger 90 scale;

Fig. 3 is a sectional view of an arrangement representing one stage in the process of making the invention;

Fig. 4 is a plan view of a mould used in the 95 process of making the invention;

Fig. 5 is a sectional view of the mould shown in Fig. 4, together with other parts showing its application;

Figs. 6 and 7 are detail views of a part used 100

in connection with the mould shown in Figs. 4 and 5.

Fig. 8 is a perspective view of the arrangement shown in Fig. 3;

5 Fig. 9 is a plan view of another mould used in the process of the invention;

Fig. 10 is a cross-section taken on line 10—10, together with other parts showing its application;

10 Fig. 11 is a cross-section of an arrangement representing a modification in the process of the invention;

Fig. 12 is a cross-section of a mould used in said modification; and

15 Fig. 13 is a sectional view of a detail showing another modification.

Having reference to Fig. 2, 1 is a stem containing the bore 2. The surface line *s* of the stem below the line *a*—*a* in Fig. 2, i. e. the 20 surface presented to the eye of the observer, is part of an ellipse, and the bore 2 is located in that focus of the ellipse which is remote from the front surface *s*. Since the part of the ellipse behind the bore is of no consequence, it may be omitted. Only so much of the glass is necessary as to place the bore 25 within it.

The principal feature of the process of producing a tubing according to the invention, 30 is the making of the tube of two separate parts of glass joined to each other in the direction of the bore and preferably in such a way as to form the bore.

Having reference to Fig. 3, 3 represents a 35 ball of glass preformed in a suitable mould similar to that shown in Fig. 12, to have in part an elliptical cross-section such that one focus lies entirely within its area and the second focus lies at the periphery. It is the 40 location of this second focus which is of importance. In the drawings, the surface line *t* below the line *b*—*b* in Fig. 3, is substantially elliptical and the second focus lies at the upper or rear surface of the ball 3.

45 To this upper or rear surface of the ball is applied a strip of glass 4 having in its contact surface a groove 5. The strip 4 and the ball 3 are joined, of course, while both are in a plastic condition.

50 The strip 4 is preformed in a mould 6 which is entirely open on one side, like an open box, and has in one of the four confining walls a slot 7 so that a rod may be entered at the free end of the wall and moved 55 bodily down to the bottom of the mould at right angle to the latter or parallel to the walls adjoining the slotted wall.

In practice, a gob of glass is gathered on 60 a rod 8 and is then placed into the mould with the rod 8 extending out through the slot 7. A forming plunger 9 is then pressed down upon the glass. The bottom of the mould is preferably curved convexly and is provided with a central rib 10 to form in the 65 glass the groove 5. Then the piece of glass

4 thus formed is taken out of the mould and, if necessary, reheated, and when both the ball of glass 3 and the piece of glass 4 are in a proper condition for joining, the strip of glass 4 is placed upon the ball, as indicated in Fig. 8 with the groove facing the surface of the ball. Then the lateral portions of the strip 4 are wiped down outwardly from the center containing the groove so as to squeeze out all air to avoid air pockets or secondary bores.

When the union is completed, the body of glass, which has the configuration of Fig. 2, is drawn down to the required size. It is understood that while Figs. 2 and 3 are of approximately like size, the ball shown in Fig. 3 on a relatively small scale, represents a ball of glass about 5"–6" in diameter, while the tubing shown in Fig. 2 on a relatively large scale, represents a thermometer tubing, the tubing retaining of course, the cross-sectional configuration of the ball of glass at the time of the drawing operation.

When the finished tubing is filled with mercury, the latter appears to transversely fill the tube from side to side, as indicated in Fig. 1 wherein 12 represents the mercury column and the space above the column is transparent. In order to emphasize the contrast between the mercury column and the space above the same, I propose to apply white enamel. This may be conveniently done by adding a layer of enamel to the ball of hot glass after the strip 4 is joined, such layer 13 being shown in Fig. 2. This layer 13, as it is disposed only a very short distance behind the bore, which is at the focus of the ellipse, and is considerably wider than the bore, appears across the full width of the tube above the mercury column and thus stands out in a maximum contrast to the dark mercury column.

To properly locate the groove 5, I preferably place the hot preformed ball 3 into a mould 14 shaped in cross-section so as to receive the ball in one definite position and then place the hot strip 4 in symmetrical position thereon. To this end, the mould preferably contains guide arms 15 pivotally carried on studs 16 and the arms 15, at their free ends, carry abutment plates 17 for definitely positioning the strip in lateral direction so that when the strip 4 is placed between the plates, the groove 5 lies in the focus of the ellipse throughout the length of the ball of glass and consequently when the glass is drawn, the bore of the tube will always be at the focus of the ellipse as intended.

The studs are preferably pivoted at their lower ends and are held in a normal upright position by springs 18. After the strip 4 has been placed into position, the arms can be readily withdrawn and the ball can be easily taken out of the mould.

The arrangement in Fig. 11 shows a slight

modification from the arrangement described. The groove 21 is provided in the ball 20 and the strip of glass 22 serves as the closure for the groove to define the bore. To 5 carry out this construction, the mould 24 is provided with a rib 25 similar to the rib 10 in Fig. 5. The mould 24 thus not only shapes the ball of glass to give it a partly elliptical shape in cross-section, as previously explained, but at the same time forms the 10 groove 21. The treatment of the ball 20 and the strip 22 is otherwise the same as described.

Having reference to Fig. 13, the glass strip 15 26 may be provided with a groove 27 for receiving a colored enamel. The position of the groove 27, after the strip 26 is joined to the ball, is so close to the bore that in the tubing drawn from it, the groove 27 is almost at the 20 focus. However, the groove may be made slightly wider than the bore to make up for the difference in the location.

In the foregoing I have attempted to describe only the broader aspect of the invention and one particular method of carrying it into effect. It is understood that other methods and other auxiliary apparatus may be resorted to for accomplishing the object of the 25 invention.

30 The principal advantage of a thermometer tubing according to the invention is, as previously suggested, the optical effect whereby the mercury column, which is ordinarily not readily discernible, at least not in thermometers of very small bore, such as clinical thermometers, is magnified to a maximum and, in fact, visually occupies the whole stem from side to side.

Another very material advantage is the 40 position of the white or colored layer immediately to the rear of the bore. By this disposition the light or color effect, as the case may be, is so close to the bore that the background thus produced has a maximum contrast effect and in addition visually appears in the same vertical plane as the mercury column. The reduction of the thickness of glass between the bore and the rear surface of the tube to a negligible quantity, as this may 45 be accomplished particularly in the form shown in Fig. 11, is instrumental in effecting a maximum of contrast between the mercury column and the enamel background.

In addition, the amount of enamel for the 50 colored member may be very small since the width of it need not materially exceed that of the bore. The advantage of this feature is the elimination or at least material reduction of such strains in the glass stem as are due to 55 the well known differential action of glass and enamel as to expansion and contraction.

While the cross-section of thermometers according to the invention is not strictly elliptical, it differs from an elliptical cross-section 60 only in some comparatively small detail.

For the sake of simplicity of expression, the terms "elliptic space" and "elliptical cross-section" have been employed in a general way and not in the strict sense.

I claim:

1. In a process of making thermometer tubing, the steps which consist in forming a body of glass in a mould so as to define in one surface thereof a groove, joining thereto while in plastic condition another piece of glass to form a cover for said groove and then drawing the resulting body of glass. 70

2. In a process of making thermometer tubing, the steps of forming a bore, which consist in forming a groove-forming rib on the surface of a relatively large body of metal, pressing a body of glass in plastic condition against the said surface, joining thereto while in plastic condition another piece of glass to form a cover for said groove and then drawing the resulting body of glass. 75 80 85

In testimony whereof I affix my signature.
